VIEW TRANSMISSION SYSTEM

Randall C. Ballard, Audubon, N. J., assignor to Westinghouse Electric & Manufacturing Company, East Pittsburgh, Pa., a corporation of Pennsylvania

Continuation of application Serial No. 519,062, February 28, 1931. This application December 23, 1937, Serial No. 181,359

3 Claims. (Cl. 250—27)

This invention relates to television and facsimile-transmitting systems and it bears particular relationship to systems especially adapted for the transmission and reproduction, at a distance, of moving pictures or the like.

This application is a continuation of my application Serial No. 519,062, filed February 28, 1931. The primary object of this invention is to provide improved scanning and reproducing means 10 in systems of the type referred to above.

Another object of this invention is to provide means for obtaining faithful and undistorted reproduction of moving pictures.

Another object of this invention is to provide 15 means whereby accurate synchronization may be maintained.

Another object of this invention is to provide scanning means at the receiving end of a facsimile-transmitting system utilizing saw-tooth 20 wave forms in connection with electromagnetic deflectors for cathode rays.

Additional objects of this invention will be disclosed in the following description taken in conjunction with the accompanying drawing wherein, 25 in the single figure is a diagrammatic view of a facsimile-transmission-and-receiving system embodying the invention.

Referring more particularly to the drawing, the apparatus illustrated therein comprises a film- 30 storage reel 1 from which a moving picture film 3 is withdrawn by a take-up reel 5.

Neither the driving mechanism employed in the operation of the film mechanism nor the usual apparatus which is normally employed in 35 guiding the film before the source of light is disclosed, inasmuch as any of the conventional type apparatus may be employed for this purpose.

The light from a fixed source 7 is reflected upon the film from an oscillatory mirror 9 that is so 40 arranged as to periodically cause the reflected ray to pass from side to side of the film. Any suitable means may be provided for producing this oscillatory condition, such means being broadly indicated by an inductor 11 energized 45 from a source of alternating current 13. A photoelectric cell or other light-sensitive device 15 is disposed immediately behind the film 3 to receive the light which has become modulated by the varying degree of shading of the picture elements 50 as the light passes therethrough. As the film travels in a downward direction, indicated by the arrow, the ray of light reflected from the oscillatory mirror 9 falls upon each frame of the film, defining a substantially sinusoidal path across 55 the picture area, the longitudinal distance on the film between successive reverses of the path being a function of the speed of travel of the film and the rate of vibration of the mirror.

The output current from the photo-cell 15, 60 after it has been sufficiently amplified, is utilized

to modulate a carrier wave in any well known manner for either radio transmission to distant receivers or transmission thereto over metallic conductors. These details are not disclosed specifically as they do not comprise parts of this invention. This portion of the system, therefore, is merely illustrated in the form of a rectangle labeled "Transmitter" inserted in the circuit, this apparatus constituting the transmitting portion 5 of the system.

One of the output terminals of the transmitting apparatus is connected to a distantly located receiver by means of a conductor 17, and the other terminal of the transmitter is grounded. When the transmission is by electromagnetic radiation, the metallic conductor is replaced by 10 an antenna. The distantly located receiver might 15 preferably comprise a plurality of high-frequency amplifying stages, a demodulator and an audio-frequency amplifier if the picture transmission is 20 accomplished through the modulation of a carrier wave.

A receiving apparatus of this type embodies conventional circuits preferably of the superheterodyne type covering a wide frequency band. 25 The particular type of receiver employed constitutes no part of the present invention, since any receiving apparatus of conventional design which will give an output proportional to that of the received signal that represents the varying translucence of the transmitted film, may be employed. The amplitude of the output must be sufficient to control the magnitudes of an electron stream in a cathode ray tube 19 and, consequently, the brilliancy of the fluorescence, where the cathode stream therein strikes a screen 21 at the end of the tube.

The cathode ray tube is preferably of the type 30 having a thermionic cathode 23, a control element 25, and anode 27, an inductance 29 producing an electromagnetic field for deflecting the electron stream transaxially in a direction indicated by the arrows 31, and another similar inductance 33 positioned at right angles to the inductance 29 for deflecting the electron stream transaxially 35 in a direction at 90° to that produced by the latter. The control electrode 25 of the cathode ray tube is connected to the cathode thereof through a source of biasing potential 35 and an input impedance comprising resistor 34 of approximately 40 50,000 ohms, the output circuit of the receiver being coupled to the control electrode 25 by a condenser 37 having a value of approximately 1 45 mfd.

The potential gradient between the control electrode 25 and the cathode 23 comprises two 55 components, a direct-current biasing potential from the direct-current source 35 and an alternating potential representative of the modulation of the incoming signal. Since the magni- 60

tude of the electron stream between the cathode and the anode is a function of the potential between the control electrode and the cathode, and, since the fluorescence of the screen 21 at the 5 end of the tube 19 is a function of the magnitude of the electron stream or the cathode ray passing through the electrode 25, it will be apparent that the brilliancy of the fluorescence will, at any instant, be proportional to the picture modulation. One terminal of the inductance 29, hereafter referred to as the deflecting coil, is grounded and the other terminal is connected by a conductor 39 to one of the terminals of the alternating-current source 13 which causes the mirror 9 to 10 oscillate. The other terminal of the alternating-current source is connected, through ground, to the winding of the inductor 11 which is associated with the oscillatory mirror and which functions to cause the vibrational movement 15 thereof.

The deflecting coil 29, connected in circuit with the mirror-actuating coil of the inductor 11, produces the horizontal component in the scanning operation which occurs at the receiving end of 25 the system. To provide means for producing the vertical scanning component at the receiving end of systems of the type described for the transmission and reception of motion pictures, it has been customary, according to the prior art, to 30 employ the charge voltage across a condenser which was charged at a constant current rate through a device, such as a saturated tube having a tungsten filament. This charge voltage was applied directly to electrostatic deflection plates 35 built into the cathode ray tube structure, and the electron beam was thereby caused to shift in a vertical direction. A system of this type is described in United States Patent 1,786,812.

It has been found, however, that this means 40 does not produce ideal results in that residual charges are apt to develop on the glass walls of the tube beneath the deflection plates, which causes the velocity of the beam, in its vertical scanning movement, to change from that of a 45 uniform to a non-uniform velocity, with the result that distortion of the received images occurs on the screen of the tube. Another disadvantage resulting from the use of electrostatic deflection plates for this purpose was that the effect of the 50 electrostatic deflection produced distortion of the focus of the spot of light striking the fluorescent screen.

It must be borne in mind that the characteristics of the vertical scanning are entirely different from those of the horizontal scanning. In the one, namely, the horizontal, the velocity of travel of the cathode ray is substantially uniform in both directions and it is a comparatively easy problem to cause the ray to oscillate at a uniform 55 velocity by applying a sinusoidal voltage to the deflecting coil. When providing the vertical scanning component however, the ray is caused to sweep across the screen at one velocity and return to its starting place at a much higher velocity.

This change in velocity in opposite directions has been accomplished, as described, by means of electrostatically charged plates but, insofar as 70 applicant is aware, no other means has ever been suggested whereby the cathode ray could be made to sweep across the screen at different velocities and in opposite directions when electromagnetic deflecting means are employed which overcome to a large extent the disadvan-

tages noted above in respect to the use of electrostatic plates for this purpose.

Accordingly, this invention comprises an improvement upon the scanning means of the prior art by providing electromagnetic means for producing the results obtained by the electrostatic means of the prior art, at the same time energizing the electromagnetic deflectors by voltages of substantially saw-tooth waveform in an efficient manner, with the consequent result that the 10 received pictures will more faithfully reproduce the details of the originals.

The synchronous operation of the electromagnetic means referred to is accomplished by a make-and-break device forming part also of the 15 subject-matter of United States Patent 1,786,812 previously referred to.

As the film travels from the storage reel 1 to the take-up reel 5, it causes the rotation of a toothed wheel 41, the teeth of which engage a series of marginal perforations in the film. The toothed wheel is connected through a shaft to a disc 43 that is provided with a plurality of peripheral projections 45. The free end of a contact member 47, by reason of spring action is caused to ride upon the periphery of the disc 43 except at such times as the projections on the disc cause the contact member to be lifted from the periphery. The diameter of the disc and the number of projections thereon are so chosen that one of the projections 45 raises the movable contact member 47 to engage a contact member immediately above it at each instant during the travel of the film 3 that the scanning ray is about to leave the upper edge of one of the pictures of 35 the film.

In the operation of the system, the film, in its travel between the storage and the take-up reels, is exposed to a beam of light from the oscillating mirror 9 which moves in a substantially sinusoidal path across the film at a frequency corresponding to that of the alternating-current source. At the same time, since one terminal of the alternating-current source 13 is connected to ground through the actuating winding of the 40 mirror, and the other terminal is connected to ground through the deflecting coil 29 nearest the anode of the cathode ray tube, the electron stream in the cathode ray tube will be caused to oscillate from side to side in the direction of 45 the arrows 31, at the same frequency that the ray of light is being caused to traverse the moving film. One coordinate of the scanning operation at the receiving end is accordingly provided by reason of the fact that the same source of alternating current actuates both the mirror and the 50 cathode-ray beam.

It is necessary, however, to provide, at the receiving end, the other coordinate of the scanning operation corresponding to the longitudinal motion of the film at the transmitting end. Heretofore, as stated above, this coordinate was provided by the gradual building up of a charge upon a condenser connected across a pair of deflecting plates. The gradual building up of the 55 charge caused the beam of electrons to sweep from one end of the screen to the other in the same time that it takes one picture of the film to pass through the light beam reflecting upon it. During the interim between the pictures on 60 the film, it is necessary that the electron beam be brought back to its initial position before the light beam reflected from the mirror 9 begins to scan the succeeding picture. In other words, this time element will be equivalent to the time 75

it takes for that portion of film between pictures to traverse or pass through the light beam. Should the electron beam, for any reason, be slowed up on its return to its initial starting position, it will be apparent that distortion will occur in the received picture. Circumstances of this nature are prone to occur in the systems of the prior art employing electrostatic deflection plates for producing the vertical scanning component at the receiving end, this being caused by reason of the residual charges building up on the glass walls of the tube. Accordingly, by employing electromagnetic means in lieu thereof, this possible defect is eliminated.

15 The vertical scanning component is produced in accordance with this invention by a gradual building up of the magnetic field, and the return of the electron stream to its initial position is brought about by a sudden collapse of the field 10 thus build-up. These results are accomplished by means of a saw-tooth voltage produced by a generator of saw-tooth waveform, the output of which is coupled in a specific manner to the magnetizing coil, the operation of the system being 15 controlled by the make-and-break device actuated by the movement of the moving-picture film.

The circuit for producing and utilizing the saw-tooth scanning potentials comprises a transformer 49, the primary winding of which is connected 20 across the make-and-break device in series with a source of direct-current potential 51. The secondary of the transformer constitutes the input circuit to a hot-cathode grid-glow tube 53 having a cathode 55, grid 57, and an anode 59 25 therein. The cathode is designed for alternating-current operation, its energy being derived from the secondary of a transformer 61 coupled to some suitable and convenient alternating-current source, not shown here.

30 The output circuit of the grid-glow tube 53 comprises a resistor 63 in series with a source of high potential of approximately 2000 volts, the resistor 63 being connected to the positive terminal of said source, the negative terminal of which is grounded. In series with the resistor 35 and one terminal of the high potential source is a condenser 65 in such position as to receive a charge from the source of potential through the resistor 63. The midpoint of the cathode of the grid-glow tube is grounded for stabilizing 40 purposes. The resistance 63 in the plate circuit of the tube 53 functions to limit the charging current for the condenser 65 to a very low value, which, for all practical purposes, is constant for 45 short periods of time. The high-voltage source potential may be the same as that required for the operation of the cathode-ray tube, so that no additional high-potential source is required for the purpose.

50 The condenser 65 is adapted to charge to a voltage of approximately 100 volts, at which time the impulse on the grid of the tube caused by a short circuiting of the primary by means of the make-and-break device, will cause the grid-glow tube to break down and suddenly discharge 55 the condenser.

55 At this point it may be stated again that in order to obtain deflection in the manner previously described, that is, at a certain velocity increasing at a uniform rate for the movement of the cathode ray in one direction and at a much higher velocity in the reverse direction in order to return the ray as quickly as possible to its original starting point, the deflecting means, whether electrostatic or electromagnetic, must operate under the influence of an electric current which

has a specified waveform, referred to as a saw-tooth wave. The latter is characterized by having a uniform rate of increase at a given velocity from zero to a certain magnitude in time and a rapid fall at a much higher velocity back to zero. It is highly desirable that the rate of movement of the beam be uniform in one direction, let us say, in referring to the drawing, from left to right along the axis indicated at 31, for if the scanning rate is not uniform across the entire width of the field of vision, the signal will not bear the same relation to light intensity in all parts of the field and the picture will appear to be unequally illuminated. The saw-tooth waveform voltage accomplishes this very well by its uniform rate of increase in time, and the rapid return of the scanning line is effected by the quick fall to zero value of the current. As mentioned before, the resistance capacity combination 65 and 63 in conjunction with the mechanically triggered grid glow tube providing a sudden discharge path, is the source generating a voltage of substantially saw-tooth waveform. In order to apply the voltage so obtained efficiently to the deflecting 10 coil 33, there is provided a coupling circuit including a high impedance coupling device in the form of a vacuum tube 67 of the screen grid type. The input and output circuits of this tube are so arranged by properly chosen constants of 15 the impedance elements that the effect of the inductive reactance of the coil 33 will not react upon the voltage source, or influence the linear characteristics of the output current. The electrodes of the tube 67 are connected in the conventional manner, the filament 75 being energized by a suitable source of heating current which in this case may be the transformer 61 employed for the filament of the grid-glow tube 53. Operating potential for the remaining electrodes 20 are shown schematically being obtained from taps on a voltage divider 83, which is connected across a source of approximately 600 volts D. C. Taking the potential of the cathode 11 as a reference point, it is seen that the screen 19 is at a potential more positive, the plate 81 being at the 25 most positive potential. The plate circuit includes the load resistance 87 and a coupling condenser 85 of relatively large capacity value, the purpose of which is to isolate the direct current component from the deflecting coil 33 which is effectively connected in parallel with the load resistance 87. The input circuit includes the grid 11, the grid resistor 86 which returns to a point 30 more negative with respect to the cathode 15 on the voltage divider 83. The input circuit of the tube 67 is energized by the saw-tooth voltage produced by the oscillator arrangement previously described. Due to the fact that the screen-grid tube, the function of which here is intended 35 to be only a transmission controlling element, will inherently amplify, the full output of the saw-tooth voltage source is not applied to the grid thereof, but only a portion between the condensers 69 and 73, which are in series-parallel connection 40 and act as a voltage divider.

The operation of the tube in the manner stated is largely due to its plate voltage-plate current characteristic which is substantially flat within wide limits and the judicious choice of circuit constants, whereby the retroaction of the inductive reactance of the deflecting coil is substantially eliminated. In the type of tube utilized the plate current is substantially unaffected by plate voltage variations, and this characteristic 45 of the tube plays a predominant part in the op- 50

eration of the circuit which is designed to favor such operation by virtue of the relations existing between the circuit constants. When the half cycle of oscillation is suddenly terminated by the short circuiting action of the neon tube, the plate current drops immediately to its initial starting value. The inductive reactance of the deflecting coil by the sudden collapse of the magnetic field built up by the former gradual increase of plate current, tends to resist the change and generates a back electromotive force which reacts on the plate circuit and increases the plate voltage. However, by virtue of the tube characteristic aforementioned, this change in plate voltage will not affect the plate current, hence as long as the plate current remains unaffected by any other source than the input voltage to the tube, the output current waveform will conform to the input voltage waveform.

During the interval of time when the contact 41 is riding upon the periphery of the disc 43, the plate current of the screen-grid tube 67 will gradually and uniformly build up. The magnetic field in the laminated core will start from a maximum value in one direction, decrease gradually, and uniformly pass through zero value and increase in the same manner to a maximum in the opposite direction. The resistor 81 across the condenser and coil is of such high value as not to delay the reversal of current or the reversal of the flux in the coil 33 during the periods when the reversals take place. These periods of reversal occur when contact is made at the make-and-break device producing a pulse which, due to the discharge of the condenser 65 in the plate circuit of the grid-glow tube 53 suddenly causes the grid of the tube 67 to go negative, and the current through the deflection coil quickly reverses and returns to a maximum in the opposite direction, thus bringing the cathode ray back to its initial starting point in position for the starting of the scanning operation, as applied to the succeeding picture.

The circuit described may be adapted for use with the conventional disc-type television scanning. For the horizontal scanning, the same circuit may be used, but it will be advisable to use fewer turns on the deflecting coils and to employ a five-electrode tube of higher plate current for the amplifier.

In a practical embodiment utilizing a screen-grid tube known as the type 224, the following values of circuit constants were found to give the best results in obtaining saw-tooth current in the scanning coil 33 which had an inductance of approximately 10 to 20 henries:

Resistor 86	2 megohms
Resistor 87	50,000 ohms
Condenser 85	8 micro-farads

The operating voltages for the tube 67 were adjusted for linear response and the following conditions were found to give best results, with a plate potential source of approximately 600 volts, grid bias voltage approximately 4 volts negative, screen grid voltage 100 volts positive with respect to the cathode 77.

The above values are given merely by way of example for a practical embodiment of the circuit and are not intended to limit the application thereof to circuit constants other than shown above as long as in the operation of the system a saw-tooth current is maintained in the scanning coil 33.

By reason of the fact that electromagnetic scanning devices are employed energized by saw-

tooth currents in lieu of the electrostatic means heretofore used, scanning means are obtained, the velocity of which may be made uniform and which will not be influenced by undesirable factors inherent with capacitive devices of the prior art. By reason of the fact that the velocity may be made uniform, the reproduced picture will more faithfully disclose the features of the original subjects. Synchronizing of the scanning will be correspondingly more accurate.

Various modifications and changes may be made by those skilled in the art. Therefore, while I have disclosed my invention in great detail, I do not desire to be limited thereto except as is necessitated by the prior art and the appended claims.

I claim as my invention:

1. In an apparatus for controlling the movement of a beam of cathode rays projected upon a screen, electromagnetic means arranged in proximity of said beam for controlling the transaxial movement thereof, an oscillator producing a voltage of substantially saw-tooth wave form, a transmission circuit coupling said oscillator with said means including a vacuum tube having at least an anode, a control grid and a screen grid, means for energizing said screen grid, said vacuum tube having a plate-voltage, plate-current characteristic which is substantially flat over the normal operating range of the plate current, an input circuit for said tube including said control grid and said cathode, said input circuit being energized by said oscillator, an output circuit between said anode and said cathode, said output circuit including said electromagnetic means.

2. In an apparatus for controlling the movement of a beam of cathode rays projected upon a screen, electromagnetic means arranged in proximity of said beam for controlling the transaxial movement thereof, an oscillator producing a voltage of substantially saw-tooth wave form, a transmission circuit coupling said oscillator with said means including a vacuum tube having at least an anode, a cathode, a control grid and a screen grid, means for energizing said screen grid, an input circuit for said tube including said control grid and said cathode, said input circuit being energized by said oscillator, and an output circuit between said anode and said cathode, said output circuit comprising an impedance effectively in parallel with a capacitor and said electromagnetic means.

3. In an apparatus for controlling the movement of a beam of cathode rays projected upon a screen, electromagnetic means arranged in proximity of said beam for controlling the transaxial movement thereof, an oscillator producing a voltage of substantially saw-tooth wave form, a transmission circuit coupling said oscillator with said means including a vacuum tube having at least an anode, a cathode, a control grid and a screen grid, means for energizing said screen grid, an input circuit for said tube including said control grid and said cathode, said input circuit being energized by said oscillator, and an output circuit between said anode and said cathode, said output circuit comprising an impedance effectively in parallel with a capacitor and said electromagnetic means, said impedance being of such magnitude and the operating characteristics of said tube so chosen as to produce a current in said output circuit which gradually and uniformly builds up to a maximum and then to quickly reverse.
